UNITED STATES PATENT OFFICE.

ERNST EBBINGHAUS, OF NEW YORK, N. Y.

DESIGN FOR A FLYING AND GLIDING DEVICE.

42,501.

Specification for Design.

Patented May 14, 1912.

Application filed January 24, 1912. Serial No. 673,260. Term of patent 3½ years.

To all whom it may concern:

Be it known that I, ERNST EBBINGHAUS, a subject of the Emperor of Germany, residing at Manhattan borough, city, county, and State of New York, have invented a new, original, and ornamental Design for a Flying and Gliding Device, of which the following is a specification, reference being had to the accompanying drawing, forming part thereof, in which—

Figure 1 is a plan view of a flying and gliding device, showing my new design; and Fig. 2 is a bottom plan view thereof.

I claim:

The ornamental design for a flying and gliding device, as shown.

Signed at New York city, N. Y. this twenty-third day of January, nineteen hundred and twelve (1912).

ERNST EBBINGHAUS.
